UNITED STATES PATENT OFFICE.

JOSEPH F. KRESS, DANIEL J. O'CONNELL, AND LOUIS N. OSMOND, OF PHILADELPHIA,
PENNSYLVANIA.

DESIGN FOR AN AUTOMOBILE SIGNAL-LAMP.

42,690.

Specification for Design.

Patented July 2, 1912.

Application filed March 20, 1912. Serial No. 685,066. Term of patent 7 years.

To all whom it may concern:

Be it known that we, JOSEPH F. KRESS, DANIEL J. O'CONNELL, and LOUIS N. OSMOND, citizens of the United States, residing in Philadelphia, county of Philadelphia, and State of Pennsylvania, have invented a new, original, and ornamental Design for Automobile Signal-Lamps, of which the following is a specification, reference being had to the accompanying drawing, forming part thereof.

The figure is a perspective view of the

signal light looking toward the front of the same.

We claim:

The ornamental design for an automobile signal lamp, as shown.

JOSEPH F. KRESS.
DANIEL J. O'CONNELL.
LOUIS N. OSMOND.

In the presence of—

GEO. H. WEIDNER,
CARRIE E. KLEINFELDER.
